UNITED STATES PATENT OFFICE

ROBERT E. MANN, OF VENICE, CALIFORNIA

ELLIPSOGRAPH

Application filed July 11, 1929. Serial No. 377,552.

My invention is an improvement in geometrical instruments and relates more especially to devices of this nature for the purpose of describing an ellipse and known as ellipsographs.

The primary object of my invention is to provide a mechanical device or improved trammel for the purpose of drawing ellipses of various dimensions and contemplating an arrangement of the parts whereby the device may be also adapted for drawing circles of different diameters.

A further object of my invention is to provide a mechanical device of this general character which can be easily and conveniently manipulated in connection with either pencil or pen and a wide range of adjustments made for drawing ellipses of small and large diameters without requiring a trammel frame of large dimensions, and including an attachment for the pen or pencil usable in connection with both rods and a bearing block traveling on the rim of the frame for use in connection with the device when used for drawing circles.

With these principal objects in view my invention consists in the particular construction of the parts including a frame having a circular rim and crossed slots therebetween with shiftable supporting legs for said frame, together with blocks slideable in the slots with respect to one another and rods of different lengths attachable to said blocks above and below the frame for carrying the scribe, one of the blocks being provided with a swivelled cap for adapting the device in drawing circles; all as hereinafter fully described and particularly set forth in the appended claims.

In the drawings:—

Figure 1 is a perspective view of my improved mechanical device for drawing ellipses and circles.

Fig. 2 is a top plan view of the device.

Fig. 3 is a side elevation.

Fig. 4 is a transverse sectional view on a line with one of the diametral slots.

Fig. 5 is a detail sectional view of one of the blocks adapting the device for drawing circles.

Fig. 6 is a similar view of the companion block, and

Fig. 7 is a detail view of the holder for connecting the scribe to either one of the rods.

Like numerals of reference indicate like parts in the several views of the drawings.

In carrying out my invention the main frame of the device is similar to that of an ordinary trammel and consists of a circular rim 10 with bars 11 extending inwardly from said rim in spaced pairs joined near the center of the frame as shown in the drawings to provide two diametral slots 12 and 13 which cross each other at the center of the frame, and for supporting the frame at the desired height above the drawing board three legs 14 are employed in the present instance and connected to the rim by set screws 15 and 16 (Fig. 3) the set screw 15 passing through the rim from above into the offset portion of the leg at the underside of the rim while the screw 16 extends upwardly through said offset portion into the rim whereby the legs may be disposed at any required angle with respect to the frame in the operation of the device as hereinafter explained, and more rigidly secured by screw 16 when disposed radially. The lower ends of the legs are turned outwardly to form feet 17 and for holding the device in place on the drawing board a pointed screw 18 is threaded through each foot, said screws also providing for adjusting the height of the frame.

For drawing ellipses blocks 19 and 20 are slideable in the respective slots and provided in the upper part thereof with transverse apertures or openings, 19a—20a, through which a rod 21 passes from one to the other of said blocks and carries a scribe—either pencil or pen—for drawing large ellipses, said blocks being also extended below the frame to receive an additional rod 22 for drawing small ellipses within the zone of the supporting legs, the rod 22 passing through transverse apertures 19b and 20b in the blocks. By reference to Figs. 5 and 6 it will be seen that these blocks are made in two parts or members for connection to the frame, one of said members being provided with a rectangular projection 23 extending through the

slot in the frame and the companion member having an integral screw 24 threaded into said other member, with outwardly projecting flanges 25 on both of the members for 5 sliding engagement with the upper and lower edges of the bars forming the slots, and in order to adapt the device for drawing circles the block 19 is provided at its upper end with a swivelled cap 26 having a transverse opening 27 to receive the aforementioned rod 21 which is secured to the swivelled cap by means of a set screw 28, said swivelled cap being rotatably connected to the block by means of a peripherally grooved stem 29 extending 10 into said block and engaged by a set screw 30 (see Fig. 5). Rod 21 extending through the upper portions of the blocks 19 and 20 is adjustably connected thereto by set screws 31 and 32 (Fig. 1) and rod 22 which extends 15 through the lower portions of said blocks is likewise adjustably connected by set screw 33 threaded in block 19 and knurled nut 34 threaded on the rod against the outer side of block 20.

25 It will be understood that when a small ellipse is being drawn within the supporting legs by the use of rod 22 the other rod 21 is used as the operating lever, but when the longer rod is being used for drawing ellipses 30 beyond the supporting frame rod 22 may be removed, and in drawing ellipses of such a size that the legs in normal position (Fig. 1) would interfere said legs may be shifted as indicated in dotted lines Fig. 2, in which case 35 the longer rod of course will be used; consequently ellipses of various sizes as to longitudinal and transverse diameters may be drawn by simply adjusting the blocks with respect to each other, as for instance the distance 40 between block 19 and the scribe is set to equal the radius of the minor diameter of the ellipse and the distance between block 20 and the scribe is set to equal the radius of the major diameter, and should it be desired 45 to draw two ellipses across each other at right angles this is accomplished by placing a scribe on each projecting end portion of the rod being used and sliding the rod through so that the pencil points are at the same distance 50 from blocks 19 and 20 at each end, as will be obvious. Furthermore, when the device is used for drawing circles block 19 is positioned at the center of the frame and held in place by rod 22 (Fig. 4) which is 55 passed through the block 19 and through block 20 at one side and through a similar block 35 at the other side, said supplemental block being secured to the rod by a set screw 36 while knurled nut 34 is threaded against 60 the opposite block 20, whereby a fixed fulcrum for the rod 21 is provided so that the scribe carried by said rod may be manipulated in describing a circle. Rod 21 is graduated 65 for the accurate spacing of the blocks and scribes with respect to the longitudinal

and transverse diameters of the ellipses, and of course rod 22 may be also graduated.

Any preferred form of scribe or drawing instrument may be used, as pencil 37 or pen 38, and for convenience in connecting the 70 scribe to either of said rods I employ a holder 39 consisting of a member having a longitudinal opening 40 (Fig. 7) at one end and a transverse opening 41 at the other end to receive a rod and drawing instrument according 75 to the use of said holder with respect to said rods—the rod 22 being passed through the longitudinal opening and the shank of the drawing instrument through the other in one instance (Fig. 3) and the positions reversed 80 in the other instance or when the holder is used in connection with rod 21 (Fig. 4) with set screws 42 and 43 for connecting the holder to the respective parts; this holder thereby compensating for the distance of said rods 85 from the drawing board respectively for use in connection with the drawing instruments. However, a modified form of holder 44 may be used in connection with rod 21 as shown in Fig. 1 of the drawings and connected there 90 to by set screw 45, and in order to steady the rod 21 in describing a circle a block 46 is adjustable on said rod by set screw 47 and provided with a ball bearing 48 at its lower end adapted to travel around the rim of the 95 frame, as shown in Fig. 4.

From the foregoing description in connection with the accompanying drawings the construction and operation of my improved device for drawing ellipses and circles will 100 be readily understood, the rods being guided by the blocks traveling in the crossed slots after the manner of a trammel, in the present instance the shorter rod 22 being used for small ellipses within the zone of the legs 105 and the longer rod 21 for drawing ellipses beyond the zone of the legs, the latter being shifted so as to not interfere with ellipses in the intermediate zone, and for drawing circles the blocks 19, 20, and 35 are connected 110 so that the block 19 will be held at the center of the frame with the attachment 46 adjusted so that the ball bearing at the lower end thereof will travel around the circular rim of said frame, it being understood that for the purpose of drawing smaller circles with the rod 22 block 19 can be reversed and intermediate circles drawn by shifting the legs 115 as explained with reference to drawing ellipses.

The device is light in construction and provides simple and effective means for accurately drawing true ellipses of any desired size as to longitudinal and transverse diameters, the holder which is used in connection with the rods permitting the use of pen or pencil of the kind used in connection with other mechanical instruments, as compasses, etc., it being understood that the form of blocks and cooperating attachments herein 125 130

shown and described may be varied in detail and other modifications resorted to in carrying out my invention within the spirit and scope of the claims.

I claim:—

5 1. An ellipsograph comprising a frame having supporting legs and crossed diametral slots, blocks slideable in the slots and having portions thereof projecting above and below the frame, a rod detachably connected to the upper portion of the blocks and extending beyond the frame for drawing large ellipses, a rod detachably connected to the lower portions of the blocks, for drawing 15 small ellipses within the legs of the frame and a scriber carried by said rods.

2. A device for drawing ellipses and circles comprising a frame having crossed diametral slots and supporting legs at the outer edges of said frame, a pair of blocks reversible and slideable in the slots and having portions thereof projecting above and below the frame, a long rod connected to the upper portions of the blocks and adjustable longitudinally therein for drawing ellipses beyond the supporting legs of the frame, a shorter rod longitudinally adjustable in the lower portions of said blocks for drawing smaller ellipses within said supporting legs, a swivelled cap at the upper end of one of the blocks for using the device in drawing circles, and means for connecting each pair of blocks together.

3. A device for drawing ellipses and circles comprising a circular frame having crossed diametral slots and supporting legs at the outer edges of said frame, a pair of blocks reversible and slideable in the slots and having portions thereof projecting above and below the frame, a long rod connected to the upper portions of the blocks and adjustable longitudinally therein for drawing ellipses beyond the supporting legs of the frame, and a shorter rod longitudinally adjustable in the lower portions of said blocks for drawing smaller ellipses within said supporting legs, a swivelled cap at the upper end of one of the blocks for using the device in drawing circles, means for connecting each pair of blocks together, and a block adjustable on the rod in the upper portions of the blocks and having a bearing at the lower end thereof to travel around the circular rim of the frame for supporting said rod in drawing circles.

55 4. A device for drawing ellipses and circles comprising a circular frame having crossed diametral slots, legs pivotally secured to the outer edges of the frame for supporting the same above the work, a pair of blocks reversible and slideable in the slots and having portions thereof projecting above and below the frame, a long rod detachably connected to the upper portions of the blocks and on which said blocks are adjustable longitudinally with respect to each other for drawing

ellipses beyond the supporting legs of the frame, a shorter rod detachably connected to the lower portions of the aforesaid blocks and on which said blocks are adjustable longitudinally with respect to each other for drawing ellipses within said supporting legs, a swivelled cap at the outer end of one of the blocks for using the device in drawing circles, and means for connecting each pair of blocks to hold the block with the swivelled cap at the center of the frame; together with a block adjustable on one of the rods for traveling on the rim of the circular frame when the device is used in drawing circles.
